UNITED STATES PATENT OFFICE.

FREDERICK M. BETZ, OF HAMILTON, OHIO, ASSIGNOR TO THE OHIO MACHINERY
MANUFACTURING COMPANY, OF CINCINNATI, OHIO, A CORPORATION OF OHIO.

PRESSING-MACHINE.

1,089,385.

Specification of Letters Patent.

Patented Mar. 3, 1914.

Application filed February 12, 1912. Serial No. 677,128.

To all whom it may concern:

Be it known that I, FREDERICK M. BETZ, a citizen of the United States, residing at Hamilton, in the county of Butler and State of Ohio, have invented certain new and useful Improvements in Pressing-Machines, of which the following is a specification.

My invention relates to an improvement in pressing machines, primarily of that class for pressing garments and the like, in which a moistened cloth is usually placed over the article to be pressed.

One of the objects of my invention is to provide an ironing or pressing machine, with a heated presser head movable to and from a table or platen, with means for exerting pressure upon the head when the same is in operative position.

Another object of my invention is to provide a pressing machine with a movable head and means for presenting a moistened cloth between the head and table, together with means for locking the cloth supporting frame in its position for use and with means for releasing the same simultaneously and automatically during the movement of the presser head.

Another object of my invention is to provide a machine for pressing clothes, having a stationary work-receiving table or buck, and a presser head swingingly mounted, so as to move to and from the table in one instance, its heater base brought to a plane with and over the table during its pressing operation, and movable to a position to offer accessibility to the table, and a sponging cloth secured to a frame movable toward and from the table, intermediate of the table and presser head and capable of moving either independent or simultaneous with the presser head and the cloth adapted to be engaged by the head-pressing surface in one position, in which instance the frame telescopically engages with the heater head. The independent movement of the sponging cloth enables the same to be adjusted over the goods to be pressed, offering free accessibility to the upper surface of the sponging cloth, to moisten the same manually or otherwise before the presser head is brought into operation.

The features of the invention will be more fully set forth in the description of the ac-

companying drawing, forming a part of this specification, in which:

Figure 1 is a side elevation of the machine, Fig. 2 is a detailed view of the lower portion of the pedestal illustrating the treadle forming pressure means for the presser head in an operative position. Fig. 3 is a detailed top plan view of the presser head and sponging cloth frame. Fig. 4 is an enlarged section on line *v*, *v*, Fig. 3. Fig. 5 is an enlarged section on line *x*, *x*, Fig. 3. Fig. 6 is a detailed elevation on line *s*, *s*, Fig. 1, of a portion of the frame, supporting locking mechanism for the pressing cloth frame and the releasing means therefor movable with the presser head mechanism. Fig. 7 is an enlarged section on line *y*, *y*, Fig. 3. Fig. 8 is a horizontal section through the presser head illustrating in top plan view a modified form of burner and deflector therefor. Fig. 9 is a section on line *v*, *v*, Fig. 8. Fig. 10 is a vertical section through one end of the presser head, illustrating an end view of the burner and deflector. Fig. 11 is an enlarged section on line *x'*, *x'*, Fig. 8.

1 represents the pedestal upon which is supported the plate 2.

3 represents the table-supporting pedestal mounted on the plate 2, upon which is mounted the pressing table 4. The table 4 may be provided with padding or cushioning material upon its upper surface and inclosed with a cloth cover or the like and the same may be of such form or construction requisite to present the proper surface for ironing or pressing cloth.

5 represents an upwardly projecting bracket upon which is mounted an arm 6 of the pressing head 7. The head 7 is movable to and from the table 4 and swings from one position to another by means of the handle 8.

Of course, it is obvious that the head can be swung into and out of commission and relatively to and from the table by any well-known means manually operated or otherwise, without departing from the features of my invention.

As illustrated in the drawing, I have provided means operated by a treadle for imparting additional or final pressure to the head in a pressing operation.

9 represents a treadle lever pivotally supported upon the pedestal 1 and provided

- with a yoke 10, between the limbs of which is pivotally mounted the pawl 11.
- 12 represents a rod projected through and guided by the bracket 13, secured to the pedestal 1. The rod 12 is pivotally connected to the pressing head arm 6.
- 14 represents a counterbalance weight fixed to the rod 12 to compensate for the weight of the head. The rod 12 is provided with a series of notches 15, into which the pawl 11 engages for exerting the treadle pressure to the rod 12 and head 7. The pawl 11 is adapted to be automatically controlled relative to the rod 12, so as to permit free manual movement of the head independent of the treadle control thereof, which is accomplished as follows:—16 represents an arm formed on the pawl 11, adapted to engage a cam bracket or plate 17, fixed to and projected from the pedestal 1. 18 represents a spring, one end fixed to the treadle 9, with the opposite end engaging the pawl 11 and exerting pressure against the same in a direction toward the notches 15, of the rod 12. In the normal position of the treadle 9, as shown in Fig. 1, the arm 16, of the pawl 11, engages the cam plate 17 and maintains the pawl out of engagement with the notches 15 and is not released until the forward end of the treadle lever 9 is swung downward, as shown in Fig. 2. 19 represents a coil spring, one end of which is fixed to the lever 9, its opposite end to the pedestal 1, for automatically returning the treadle lever to normal position when released by the foot of the operator. The release of the treadle lever 9 will cause the arm 16, of the pawl 11, to engage the inclined surface 20, of the cam plate 17, thereby swinging the pawl out of engagement and away from the notches 15. This means of connection between treadle lever 9 and rod 12 maintains the head in a condition to be freely swung to and from the table without coördinately moving the treadle upon each movement of the head, while at the same time treadle pressure can be applied whenever required.
- 50 A series of notches 15 are shown, one of which is to be engaged by the pawl in operation, the plurality being provided in order to adjust the position of the lever mechanism for the pressing operation in proper relation to the thickness of the padding used on the table 4.
- In operation, the head is brought down over the table 4 manually, the operator grasping the handle 8, after which the treadle is operated for exerting additional or final pressure to the degree required for the work. The head 7 is of hollow formation provided with the top plate 21. This plate serves as a casing for the gas burner mounted therein and is provided with a series of openings for the escape of products of combustion and to admit air to the burners. 22 represents the base or pressing plate of the head secured to the casing member 21. 23 represents the burner mounted within the casing head member 21. Said burner may be of any form of construction, or a series of burners, to uniformly heat the surface of the plate 22. 25 represents a supply pipe for the burner projected through the casing member 21 and is adapted to be moved or swung with the head by employing universal or swivel couplings mounted relatively with the axis, or fulcrum, of the swinging head, or flexible tubing may be employed, connected to the pipe extension 25, or any well-known means may be provided for conducting the fuel supply to the burner which will not interfere with the movement of the head.
- To assist in retracting the head from the table after a pressing operation, I provide the following tension mechanism effective only toward the limit of the pressing movement of the head, see Fig. 1. 26 represents a coil spring, one end mounted within a bore in the counterbalance weight 14, the opposite end connected to a rod 27, said rod being slidably mounted within a bore formed in the bracket 13. The rod 27, at its free end, is provided with a nut or head 28, adapted to engage against the bracket 13, to restrict the movement of the rod when the presser head is brought close to, the table to expand the spring 26 sufficiently to aid in raising the head initially and provide a relief for the operator. The rod is provided, to allow an idle movement free from tension to the presser head mechanism during partial movements thereof toward the table.
- A universal practice in pressing cloth or wearing apparel by old fashioned hand operations, is to moisten the goods before pressing, and this is accomplished by the use of a moistened cloth, designated as sponging cloth applied over the goods over which the heated iron is moved under pressure. A material departure from this time-tested sponging cloth method is not herein contemplated, but, on the contrary, I propose an invention in the nature of a mechanical organization serving to relieve the operator of much of the manipulative labor, inconvenience and slowness of the old-time hand work, while yet retaining and accentuating all the good features of such practice, so as to enable even an unskilled worker through the aid of my instrumentality to attain speed, efficiency, uniformity, freedom from danger of local scorching, and high quality results.
- The moisture of the sponging cloth being repelled by the heated iron first penetrates and to a requisite degree initially dampens

the goods, softens or renders plastic the fiber and enables them to yield freely under pressure, and conditions the texture, so that upon a continued application of a heated iron under the maintained pressure, the moisture of the fibers is thereupon converted into live steam that forthwith leaves the fibers so that they now become dried and a permanent set and smooth finish is obtained. The heated iron converts the moisture into steam, and when the iron and sponging cloth are removed from the goods to be pressed the steam escapes upwardly raising the nap. To accomplish such sponging operation satisfactorily, accessibility to the sponging cloth is quite a desideratum, and this is accomplished by this invention by mounting the same tautly upon a frame, with the frame mounted to move to and from the table of the machine and preferably intermediate of the table and heater head. Thus, the cloth can be adjusted over the work, and its upper exposed surface moistened to the degree required by passing a wet sponge over the same. This operation being entirely under the close unimpeded scrutiny of the operator, he is enabled very advantageously to moisten such portions differentially if necessary, to produce the most satisfactory pressing of the work. This is accomplished and facilitated by the following instrumentalities:—29 represents a frame secured to the levers 30 which are fulcrumed concentrically with the arm 6 of the presser head and preferably adjacent to the outer sides of the bearings of the bracket 5 so that the sponging cloth and presser head base can be brought in parallelism upon the table. This enables the members to be moved as a unit toward the table. The levers 30 are each provided with a weight 31 to move the frame to a normal position. 32 represents a frame member upon which the sponging or pressing cloth 34 is drawn and secured, as illustrated in Figs. 4 and 7 and held by the thumb pins 35 while the frame member 32 is secured to the frame 29 by the fastening screws or bolts 33. The frame 29 has a downwardly projected marginal flange, the edge of which engages into a groove marginally formed in the upper surface of the frame member 32 which assists in holding the cloth upon said member and tautly stretches it across the same.

The pressing cloth frame is constructed to telescopically engage the presser head so that the plate 22 can be brought into contact with the pressing cloth during a pressing operation, but the parts are so arranged that the cloth does not engage said plate in an inoperative position. This is effected by limiting the upward movement of the levers 30 which engage with the pins 36, projecting from the arm or bracket 5.

From the foregoing it will be observed that my invention in general comprises a presser head normally positioned remotely from the table and pivotally mounted so as to move into parallelism with the table and counter-balanced for easy manual movement to and from the table, and free from the treadle mechanism during such movement. The treadle mechanism, in a normal position of the presser head is not in engagement or connection with the presser head, and therefore, the presser head is relieved of resistance to such an extent, which is quite an advantage to the operator, for substantially no manual labor is required merely to swing the presser head into position preparatory to the application of pressure.

The sponging cloth holder is likewise freely movable into parallelism with the table, and manually moved independently of the head, and antecedently thereof, to bring the cloth over the garment on the table to afford free access to the cloth, so that it can be manually sponged, and the presser head subsequently moved toward the previously positioned holder, registering therewith to bring the heater plate surface in direct contact with the sponging cloth.

As the pressure cloth frame is weighted so as to automatically swing to an inoperative or normal position, provision has been made to lock the frame against such movement until after the presser head has been moved downward over the table. This feature avoids the necessity of the operator holding the frame downward while he is sponging or moistening the pressing cloth, but it may be regarded as a subsidiary feature to the swinging sponging cloth holder, readily susceptible to modification or omission, without destroying the efficiency of the machine.

In Fig. 6, the preferred means are illustrated for locking the sponging cloth frame, which comprises a latch plate 35^a, slidably mounted upon a limb of the bracket 5. This plate is provided with longitudinal slots, through each of which a screw 36^a passes engaging with said limb. 37 represents a lever pivotally connected to the bracket 5 and having connection with the latch plate 35^a and the slide plate 38, said slide plate 38 is mounted substantially the same as latch plate 35^a, with one end projected in the path of the cam 39, fixed upon the arm 6. 40 represents a spring connected to one end of the lever 37 for exerting tension upon the slide plate 38 and latch plate 35^a to move them outwardly. Thus, when the sponging cloth frame is moved downward over the pressing table, the latch plate 35^a will engage beneath the lever 37 in rear of the pivot and hold the same in such position until released by moving the presser head downward, which moves 130

ment will bring cam 39 into engagement with the slide plate 38, shifting the lock members 35^a, 37 and 38, and release the sponging cloth frame, permitting the same 5 to be moved upward simultaneously with the presser head.

With the form of burner and deflector as illustrated in Figs. 8 to 11, provided within the presser head, I am enabled to uniformly 10 heat the base or pressing plate 22, and with a smaller consumption of fuel than required in the type of burner as illustrated in the burner of Fig. 3, and is therefore, the preferred form utilized within the head.

15 The burner comprises a longitudinal extended tube or pipe 41 intermediately connected with the supply pipe 25, said burner being provided with a series of orifices 42 located to direct the products of combustion 20 toward the base plate 22 of the presser head, striking the longitudinal deflector plate 43 below the burner, which plate is slightly spaced from the base plate 22, and which directs the products of combustion upwardly 25 toward the deflector plate 43^a projected horizontally from the axial line of the burner tube 41 as illustrated in Figs. 10 and 11, and extended longitudinally the entire length of the burner tube 41. This plate 43^a deflects 30 the products of combustion downwardly toward the base plate 22, distributing the same uniformly over said base plate, which uniform heating of the base plate is essential in order to properly press the clothing within 35 in the area of the presser head.

Having described my invention, I claim:—

1. In a machine of the class described, a presser head, means within said head for heating the same, a table, said presser head 40 being mounted to swing to and from said table, a frame for supporting a sponging cloth mounted to swing to and from the table, means for locking said sponging cloth frame in its position for use, and means for 45 releasing the same upon a movement of the presser head toward the table.

2. A machine of the nature disclosed, combining a frame, a garment supporting table, a presser head pivotally mounted on the 50 frame and movable into parallelism with the table, a sponging cloth holder swinging about the axis of the presser head and independently movable into parallelism with the table, the normal position of the presser head offering accessibility manually to sponge the holder cloth, and means for retaining the sponging cloth holder in its position over the table and releasable during the movement of the presser head toward 55 normal.

3. A machine of the nature disclosed, combining a frame, a work-supporting table, an open frame holder for a sponging cloth having radiating lever arms pivotally 60 mounted on said frame to swing the holder

over into proximity with the table, and automatically movable to its normal position, a presser head having radiating lever elements pivoted about the axis of the lever arms of the cloth holder to swing the head toward the table into contact with the sponging cloth, retaining means for maintaining the holder in its position over the table preparatory to the movement of the presser head and adapted to be automatically released to enable said holder to swing simultaneously with the head during its return. 70

4. A machine of the nature disclosed, combining a frame, a work-supporting table, an open frame holder for a sponging cloth having radiating lever arms pivotally mounted on said frame to swing the holder over into proximity with the table, a presser head having radiating lever elements pivoted about the axis of the lever arms of the cloth holder to swing the head toward the table into contact with the sponging cloth, retaining means for maintaining the holder in its position over the table preparatory to the movement of the presser head and adapted to be automatically released to enable said holder to swing simultaneously with the head during its return, treadle and lever mechanism adapted to be brought into operative connection with said presser head element during abnormal position of the head to exert a pressure upon the intervening sponging cloth and garment on the table. 80

5. A pressing machine having a work-supporting table, a presser head movable toward and from the table, a sponging cloth holder having its cloth adapted to be positioned over the work on said table, with the exposed surface thereof accessible for manually moistening, a treadle for applying pressure to bring the members forcibly into contact, a connecting ratchet bar in pivotal connection with said presser head, pawl mechanism mounted on said treadle, and means for directing said pawl toward and into engagement with the ratchet elements of said bar during a pressure movement of the treadle, and release in a reverse movement. 105

6. A machine of the nature disclosed combining a frame, a garment supporting table, a presser head pivotally mounted on the frame and movable into parallelism with the table, a sponging cloth holder pivoted concentrically with the presser head and movable independently thereof to position its cloth parallel with the table, the normal position of the presser head offering accessibility to the cloth when the latter is in its operative position. 120

7. A machine of the nature disclosed combining a frame, a garment supporting table, a presser head pivotally mounted on the 130

frame and movable into parallelism with the table, a sponging cloth holder pivoted concentrically with the presser head and movable independently thereof to position its cloth parallel with the table, the normal position of the presser head offering accessibility to the cloth when the latter is in its operative position, and lever mechanism adapted to be brought into operative con-

nection with said presser head in its active position for applying pressure to bring the member firmly into contact.

In testimony whereof, I have hereunto set my hand.

FREDERICK M. BETZ.
